TO THE SKINNER ENGINE COMPANY, OF ERIE, PENNSYLVANIA, A CORPORATION
OF PENNSYLVANIA.

AUTOMATIC EXHAUST-VALVE.

1,111,983.

Specification of Letters Patent. Patented Sept. 29, 1914.

Application filed March 25, 1913. Serial No. 756,680.

To all whom it may concern:

Be it known that we, EDWIN F. WILLIAMS and LE GRAND SKINNER, citizens of the United States, residing at Erie, in the county of Erie and State of Pennsylvania, have invented certain new and useful Improvements in Automatic Exhaust-Valves, of which the following is a specification.

In the U. S. patent to Skinner and Williams No. 1033280, dated July 23, 1912, there is disclosed a steam engine cylinder with central exhaust ports and intermediate exhaust ports located between the central ports and the ends of the cylinder, the intermediate ports being controlled by valves which are operated by positive mechanical means for opening and closing the same.

This construction has certain advantages some of which are referred to in said patent.

The object of the present invention is to improve said construction with respect to the means for operating the intermediate exhaust valves, said valves being operated automatically; a further object of the invention is to provide a construction in which said intermediate valves are held closed when the engine is working condensing, and allowed to open and close when the engine is working non-condensing, the closed condition in the first instance being produced or permitted by the vacuum in the exhaust pipe. By making these valves automatic, the eccentric, rocker, cams, and other exhaust valve gear is dispensed with.

The invention is illustrated in the accompanying drawing which is a half section elevation of a cylinder provided with the valves referred to.

Referring specifically to the drawings, A indicates a puppet valve which controls the intermediate exhaust port at one end of the cylinder. This valve is connected to the additional piston C—D by a stem B, so that they all move. A spring H, under the valve, tends to lift the valve, and will hold it in open position against the down rush of steam as it passes by the valve and through the port O to the exhaust pipe N. This provides a free passage of the steam as the piston travels toward the cylinder head, until the piston has passed over the port above the valve A and closed it, the piston thus acting as a valve. The piston then

compresses the steam remaining in the cylinder, and this compressed steam enters the space above the piston C through the passage I, and by pressure on said piston overcomes the spring H and closes the valve A. This valve remains closed until the piston has returned, in consequence of steam admitted through the inlet valve L, and has cleared or opened the central exhaust ports M on the return stroke, which relieves the pressure within the cylinder and consequently in the space above the piston C, and the valve A is then lifted and opened by the spring H. The cycle will then be repeated as long as the engine operates and is working non-condensing.

Should the engine be operated condensing and a vacuum be created within the exhaust pipe N, the atmospheric pressure under the piston D will be relieved through the passage F, and the free air entering above the piston D through the opening E will push the piston down, thereby closing the valve A and holding it closed as long as the engine runs condensing. It is desirable, when the engine is running non-condensing to relieve the compression in the main cylinder by opening the valve A at proper times, but when the engine is running condensing this is not necessary, and it is desirable to hold the valve A closed.

G is a relief valve at the head of the cylinder.

It will be understood that the parts above described and illustrated are duplicated at the opposite end of the cylinder, and operate in the same way. The valve and its pistons are mounted in a suitable casing on the cylinder shell.

It will be seen that the action of the intermediate exhaust valves depends first on whether the engine is running condensing or non-condensing, being held closed in the former case, provided the vacuum exceeds the strength of the spring H, and being alternately opened and closed when running non-condensing, according to the amount of compression behind the main piston J.

What we claim as new is:

1. The combination with a steam engine cylinder, of an exhaust valve, means to automatically open and close said valve when the engine is running non-condensing, and

means governed by the vacuum in the exhaust pipe for holding said valve closed when the engine is running condensing.

2. The combination with a steam engine

5 cylinder having main and auxiliary exhaust ports, of a valve controlling the auxiliary exhaust port, means to automatically open and close said valve when the engine is running non-condensing, and means governed by the vacuum in the exhaust pipe for closing said valve when the engine is running condensing.

3. The combination with a steam engine 55 cylinder having a middle exhaust port and an auxiliary exhaust port between the middle port and each end of the cylinder, of a valve controlling each auxiliary exhaust port, means controlled by the pressure in the cylinder to open and close said valve when

15 the engine is running non-condensing, and means controlled by the vacuum in the exhaust pipe for holding said valve closed when the engine is running condensing.

4. The combination with a steam engine

25 cylinder having a middle exhaust port and an auxiliary exhaust port between the middle port and each end of the cylinder, of a valve controlling each auxiliary exhaust port, a spring tending to hold said valve

30 open, and a pressure operated device connected to said valve and exposed to compression in the end of the cylinder and acting to close said valve when the pressure in the cylinder exceeds the strength of the 35 spring, and another pressure-operated device connected to said valve and exposed to the vacuum in the exhaust pipe and acting to hold said valve closed when such vacuum exists.

40 5. The combination with a steam engine cylinder having a middle exhaust port and an auxiliary exhaust port between the middle port and each end of the cylinder, of a valve controlling each auxiliary exhaust port, a spring tending to hold said valve

45

open, and a differential piston connected to said valve, one part of said piston being exposed to compression in the end of the cylinder and acting to close said valve when the pressure exceeds the strength of the 50 spring, and the other part of the piston being exposed to vacuum in the exhaust pipe acting to hold said valve closed while such vacuum exists.

6. The combination with a steam engine 55 cylinder, of an exhaust valve operatively controlling the outlet of steam from the cylinder, and means governed by the vacuum in the exhaust pipe for operating said valve.

7. The combination with a steam engine 60 cylinder, of an exhaust valve, means to operatively open and close said valve when the engine is running non-condensing, and means for holding said valve closed when 65 the engine is running condensing.

8. The combination with a steam engine 70 cylinder, of an exhaust valve operative to control the exhaust from the cylinder according to the operation of the engine, and means governed by the vacuum in the exhaust pipe for either permitting the operation of said valve or rendering the same inoperative.

9. The combination with a steam engine 75 cylinder, of an auxiliary exhaust valve operative to control the exhaust from the cylinder according to the operation of the engine, and means governed by the vacuum in the exhaust pipe for either permitting 80 the operation of said valve or rendering the same inoperative.

In testimony whereof, we do affix our signatures in presence of two witnesses.
